UNITED STATES PATENT OFFICE.

GEORGE E. LEE, OF CLEVELAND, OHIO, ASSIGNOR TO THE GEORGE E. LEE COMPANY, OF CLEVELAND, OHIO, A CORPORATION OF OHIO.

AUXILIARY MELTING DEVICE.

Application filed July 12, 1922. Serial No. 574,570.

To all whom it may concern:

Be it known that I, GEORGE E. LEE, a citizen of the United States, residing at Cleveland, in the county of Cuyahoga and State of Ohio, have invented a certain new and useful Improvement in Auxiliary Melting Devices, of which the following is a full, clear, and exact description.

The present invention relates to what may be termed an auxiliary melting device for delivering melted material to a reservoir or container.

Specifically, the invention as herein disclosed is particularly adapted for use as an auxiliary molten metal feeding device for use in connection with the melting pot or crucible of such a machine as a line type casting machine or type casting machine, or lead and rule casting machine, or a machine of similar character, but it should be understood that the particular construction herein disclosed is primarily for purposes of disclosure and is not a limitation of the invention.

Reference should be had to the accompanying drawings forming part of this specification, in which Fig. 1 is an elevation with portions in section showing the device of the present invention as applied to a reservoir or pot for use in connection with a line type casting machine or analogous machine; Fig. 2 is a front elevation of the switch and switch operating mechanism on the fixed support alongside the movable reservoir showing the switch in open position, the cover of the switch box being omitted for purposes of illustration; Fig. 3 is a view similar to Fig. 2 showing the switch in closed position and the float arm in engagement with the switch actuating member and in its extreme forward position; Fig. 4 is a plan view of the switch and switch operating mechanism; Fig. 5 is a left end view of the switch and switch operating mechanism; Figs. 6 and 7 are right end and front elevations of the switch box and cover assembled showing the switch locking device; Fig. 8 is a view similar to Fig. 1 showing a modified form of the invention; Fig. 9 is a front elevation of the machine shown in Fig. 8.

Referring to the annexed drawings, the

reservoir 1 is mounted for backward and forward movement alongside of the fixed or frame member or side rail 2 of the line type or similar line or type casting machine. The reservoir 1 receives molten metal from a melting cup 3 which is supported over the reservoir 1 by means of an arm 4 pivoted to the upper end of a standard 5 which is adjustably secured to the frame member 2 by a supporting bracket 5a. The switch box 6 is adjustably secured to the top face of the supporting bracket 5a by means of cap screws 6a which extend through slots in the bottom of the switch box. As shown herein the cover of the switch box is omitted and the switch box is provided with a high rear wall 7, and a low front wall 8. A mercury switch glass 70 vacuum tube 9 is mounted within the switch box 6 in a sectional cradle 10 which is formed in two parts and clamped around the tube 9 by means of screws 10a, a rubber packing ring being provided between the tube 9 and the surrounding parts of the cradle. The cradle 10 is provided on opposite sides with laterally projecting recessed pivot bosses 11 which receive the centering pivot points 12 carried by the walls 7 and 8 of the switch box. The centering pivot point 12 is riveted to the wall 7 and the pivot point 12a is in the form of a screw with a pointed end and provided with a lock nut for holding it in adjusted position. The vacuum tube 9 has a depressed portion 13 adjacent its right end in which is secured a glass cup 14, the brim of which extends slightly above the bottom of the tube 9. A tungsten wire 15 is secured in the right end of the vacuum tube and has its end in the cup 14. A tungsten wire 16 is secured in the left end of the vacuum tube 9 with its end extending along the bottom of the tube. Flexible insulated wires 15a and 16a are connected to the wires 15 and 16 and extend to a terminal block 17 where they are connected to binding posts 17a. Wires 18 and 19 lead from the binding posts 17a to the line and to the resistance element 100 in the melting cup 3. The vacuum tube 9 is partially filled with mercury, the amount of mercury in the tube being such that when the tube is tilted or turned about its pivots

in a forward direction (to the right) and lies in a substantially horizontal position, the mercury entirely covers the brim of the cup 14 and provides an electrical connection between the wires 15 and 16 and when the tube is tilted rearwardly (or to the left) a portion of the mercury flows from the cup 14 and the level of the mercury in the rear end of the tube is below the level of the brim of the cup on the rear or left side thereof so that the connection between the wires 15 and 16 is broken. The mercury switch per se forms no part of the present invention, being an old and well known device. The front half of the cradle 10 is provided with an integral upwardly extending portion 20 which in the movement of the cradle about its pivots engages front and rear limit stops 20^a which are in the form of set screws provided with lock nuts and serve to limit the forward and rearward movements of the switch supporting cradle. An arm 21 extends upwardly from the back half of the cradle 10 and has a rear cam face 21^a. The cradle 10 has a rigid angle arm 22 extending rearwardly therefrom, the rear end of the arm 22 extending upwardly. Rigidly attached to the lower portion of the upwardly extending part of the arm 22 is an extension 23 in the form of a resilient steel strip. An adjusting screw 24 is carried upon the upper end of the arm 22 and engages a rear face of the strip 23. The adjusting screw 24 has a lock nut to hold it in adjusted position and serves to adjust the upper end of the strip 23 forwardly or rearwardly. The extension arms 21 and 23 cooperate with cradle tilting or turning and retaining devices which will be hereinafter described. The switch turn-on lever 25 is pivoted at its lower end to the side wall 7 of the switch box adjacent the bottom of the box by suitable means such as a shoulder screw 26. At the upper end of the lever 25 is a forwardly extending pawl arm 27 which is pivotally connected to the lever 25 by suitable means, such as a shoulder screw 27^a. The end of the arm 27 has an inclined face 28 which leads to a detent 29 on the underside of the arm. The arm 27 is normally supported in substantially horizontal position by means of a lug 30 carried by the lever 25 and engaging the lower edge of the bar. A weighted pull lever 31 is pivotally connected to the lever 25 intermediate the ends thereof by suitable means such as a shoulder screw 31^a, and carries a lug 32 which engages the rear edge of the lever 25 to limit the downward swinging movement of the pull lever 31 with respect to the lever 25. The pull lever 31 has a downturned rear end 33 which carries an adjusting screw 34 which has a rounded end bearing against the cam face 21^a of the cradle extension 21. The screw 34 is pre-

erably provided with a lock nut for holding it in adjusted position and is adapted to be adjusted to vary the extent of movement imparted to the cradle by the pull lever 31. The lever 25 is limited in its forward and rearward movements by means of stop lugs 35 and 35^a carried by the wall 7. A latch bar 36 is pivoted to the wall 7 beneath the pawl arm 27 by suitable means, such as a shoulder screw 37. The latch bar 36 has an inclined face 38 at its forward end and an inclined face 39 at its rear end. The inclined face 39 at the rear end of the latch bar leads to a detent 40 on the underside of the bar and is adapted to be engaged by the upper end of the extension strip 23 of the cradle, enabling the extension 23 to lift the latch bar and move into position in front of the detent 40. A lug 41 carried by the wall 7 beneath the rearwardly extending portion of the latch bar 36 serves to limit the downward movement of the rear end of the latch bar and to normally hold the bar in substantially horizontal position.

Forward movement of the lever 25 causes the pull lever 31 to move forwardly and upwardly and the rounded end of the screw 34 moving over the face of the cam surface 21^a turns the cradle 10 upwardly. As the lever 25 moves to the right, the extension 23 comes into engagement with the detent 40 on the latch bar 36 which locks the cradle 10 in its forward position, in which position the circuit is closed. The latch bar 36 holds the switch in closed position until the extension 23 is released by depressing the forward end of the bar 36. When the cradle 10 is released it turns rearwardly and downwardly by gravity breaking the circuit. A float rod supporting bracket 42 is clamped to the edge of the reservoir 1 adjacent the supporting rail 2. A bar 43 is pivoted to the bracket 42 on a horizontal pivot, the axis of which is parallel with the supporting rail 2. A float arm 43^a carrying a float 44 on its outer end is secured to one end of the bar 43. An adjustable extension 45 which extends between the pawl arm 27 and the latch bar 36 is attached to the other end of the bar 43 by means of a pivot member 46 and set screws 46^a. By means of the set screws 46^a the extension 45 may be adjusted about its pivot 46 to raise or lower its outer end with respect to the float 44. The outer end portion of the extension 45 which lies between the pawl arm 27 and latch bar 36 has an inclined face 47 along its upper edge which is adapted to contact with the inclined face 28 of the pawl arm 27 in the rearward movement of the extension 45 with respect to the switch operating members.

In the operation of the machine the reservoir 1 moves forwardly and rearwardly alongside of and parallel with the supporting rail 2 to and from the position at which

lines of type are cast. When the surface of the molten metal in the reservoir 1 is at the highest desired point the adjustable extension 45 is adjusted so that it depresses the latch bar 36 and is in a position in which it can not engage the detent 29 of the pawl arm 27 during the forward movement of the reservoir 1.

As slugs or lines of type are cast by the operation of the linotype machine, the amount of molten metal in the reservoir is reduced and the float supported by the metal is lowered. This causes the outer end of the float bar extension 45 to be raised to a position where it will engage the detent 29 of the pawl arm 27. When the extension 45 is raised to engaging position the inclined upper face 47 thereof will engage the incline face 28 of the bar 27 on the return or rearward movement of the reservoir 1 lifting the pawl arm 27 and causing the detent 29 to drop in front of the extension 45 so that on forward movement of the reservoir 1 the pawl arm 27 and with it the switch turn-on lever 25 will be pulled forwardly. The forward movement of the lever 25 moves the switch to closed position where it is held by the latch bar 36 as above described. As the lever 25 is over-weighted the pawl arm 27 remains in contact with the extension 45 and may be operated upon succeeding movements of the reservoir 1. This, however, has no effect upon the switch which is held in closed position by the latch bar 36.

As soon as sufficient metal has been melted in the melting cup 3 to raise the lever in the reservoir 1 nearly to the normal level for which the float mechanism has been set, the rise of the float lowers the outer end of the float bar extension 45 into engagement with the outer end of the latch bar 36. When in this position the float bar extension 45 depresses the forward end of the latch bar 36 and lifts the detent 40 out of engagement with the extension strip 23 of the cradle 10, releasing the cradle and permitting it to move by gravity to switch opening position.

It is thus evident that forward movement of the reservoir is essential to the turning on of the current but that the current may be turned off either during the return of the reservoir to its normal or rearmost position or while standing in the normal position, since the latch bar 36 is moved to releasing position by the power derived from the lifting of the float as the metal in the reservoir rises.

As shown in Figs. 6 and 7 a switch lock 48 is provided which consists of a bent rod 48, the free ends 49 and 50 of which are at the front and are bent respectively downwardly and upwardly to provide a pointed end. The lock member 48 is mounted for sliding movement in a keeper 51 on the switch box cover. The downwardly inclined

end 49 engages the pawl arm 27 and the upwardly inclined end 50 engages the latch bar 36. When the lock member 48 is pushed forwardly between the pawl arm 27 and latch bar 36, depressing the latch bar 36 and raising the pawl arm 27. The latch bar 36 is depressed sufficiently to release the switch and permit it to move to open position (if it should be in closed position), and the pawl arm 27 is raised high enough so that no matter how low the metal level may be, the float arm extension 45 will not rise high enough to engage the detent 29 on the forward movement of the reservoir.

Important features of the present invention are the provision of positive power operated actuating means for the switch, the power operated switch actuating means being preferably a moving part of the machine, and the provision of means responsive to the level of the melted material in the reservoir, such as a float, for controlling the actuation of the switch by the power operated means. In the form of the invention above described the movable part of the machine which actuates the switch is the movable reservoir, however, the invention is not limited to machines in which the reservoir is movable nor is it limited to the actuation of the switch by the movable reservoir. In Figs. 8 and 9 I have shown a modified form of the invention in which the switch is actuated from a moving part independent of the reservoir.

Figs. 8 and 9 show a part of a so called Eirod lead and slug casting machine, in which the metal pot or reservoir is rigidly attached to the top face of the machine frame or bed to which is also attached the melting cup supporting bracket and in which the mercury switch which is in all respects similar to the switch above described is mounted upon the melting cup supporting bracket.

Since the switch mechanism is the same in this modification as in the modification above described, the switch box is shown with the enclosing cover in position.

Since the melting cup and its supporting arm may be the same as in the modification first described, they have not been shown in Figs. 8 and 9.

The table top or bed 61 of the lead and slug casting machine is supported upon legs 62 and carries the metal pot or reservoir 63 from which the metal is forced by plunger action through a throat portion to cast leads and slugs. The metal is maintained in a molten condition in the reservoir 63 by a gas burner underneath or by other suitable means. A motor driven power shaft 64 which is in constant revolution when the machine is being operated is journaled in brackets 65 or other suitable supporting means beneath the bed 61. The metal feeder

supporting bracket 66 which carries the melting cup supporting post 67 is bolted to the bed 61 at one side of the reservoir 63 and the switch box 68 enclosing the switch mechanism is mounted upon the bracket 66. Upon the upper edge of the side wall of the reservoir adjacent the switch box 68 is attached a bracket 69 upon which is pivotally mounted a float bar 70 to one end of which is rigidly attached a float rod 71 carrying the float 72 and to the other end of which is adjustably attached the float adjusting bar 73. The float adjusting bar 73 is adjustably secured to the arm 70 by means of a shoulder screw 74 and set screws 75 corresponding to the shoulder screw 46 and set screws 46^a above described. The float adjusting bar 73 extends between a pawl arm 76 of the switch turn-on lever and a latch bar 77 which are the same as the pawl arm 27 and latch bar 36 in the modification first described, except that the pawl arm 76 has an upwardly extending detent 78 at its outer end. An upright lever 79 is pivoted at 80 to an extension of the bracket 66 and has an inturned upper end 81 overlying the pawl arm 76 and an inturned lower end 82 extending beneath the bed 61 and provided with a cam face 83 at its end. An arm 84 is rigidly attached to the shaft 64 and engages with the cam face 83 of the lever 79 during each revolution of the shaft 64 so that the lever 79 is constantly oscillated during the operation of the machine. A coil spring 85 connected to the bracket 6 and to the lever 79 exerts a pull upon the lever 79 in a direction to move the upper end thereof to the left and to hold the lever in engagement with a stop 86 below the pivot 80. When the arm 84 strikes the cam face 83 of the lever it moves the lever in opposition to the spring 85 and when the arm 84 moves out of engagement with the cam face 83, the lever 79 is returned to its original position by the spring 85.

When during the operation of the machine the level of the metal in the reservoir 63 falls below the point to which the float has been adjusted, the float adjusting bar 73 raises the pawl arm 76 of the switch turn-on lever to a position in which the detent 78 is engaged by the inturned end 81 of the oscillating lever 79 in its movement toward the right turning the switch to "on" position where it is latched as in the modification above described. When sufficient metal has been supplied to the reservoir, the adjusting arm 73 is moved downwardly into engagement with the latch bar 77, releasing the switch which moves by gravity to "off" position.

Having described my invention, I claim:—

1. The combination with a casting machine having a reservoir for material in

melted form, and means controlled by an electric circuit for supplying melted material to said reservoir, of a switch in said circuit, an actuating member which has a predetermined movement during the operation of the machine, and means responsive to the level of the melted material in said reservoir for connecting said actuating member with said switch to actuate the same. 75

2. The combination with a casting machine having a reservoir for material in melted form and means controlled by an electric circuit for supplying melted material to said reservoir, of a switch in said circuit, a reciprocating member adapted to actuate said switch, and means responsive to the level of the melted material in the reservoir for connecting said reciprocating member with said switch to actuate the 85 same. 80

3. The combination with a casting machine having a reservoir for material in melted form and means controlled by an electric circuit for supplying melted material to said reservoir, of a switch in said circuit, means for operating said switch comprising a member which has a predetermined movement during the operation of the machine, and float controlled means for 90 controlling the operation of said switch by its operating means. 95

4. The combination with a casting machine having a reservoir for material in melted form and means controlled by an electric circuit for supplying melted material to said reservoir, of a switch in said circuit adapted to be actuated by a moving part of said machine, and means responsive to the level of the liquid in said reservoir 100 for controlling the actuation of said switch by said moving part. 105

5. The combination with a casting machine having a reservoir for material in melted form and means controlled by an electric circuit for supplying melted material to said reservoir, of a switch in said circuit, means for moving said switch to closed position, means for retaining said switch in closed position, and means responsive to the 110 level of the liquid in said reservoir for connecting said switch with said moving means and for releasing said switch from said retaining means. 115

6. The combination with a casting machine having a reservoir for material in melted form and means controlled by an electric circuit for supplying melted material to said reservoir, of a switch in said circuit, a pivotal support for said switch counterbalanced to normally hold said switch in open position, means for moving said switch to closed position, means for retaining said switch in closed position, and means responsive to the level of the liquid in said reservoir 125 130

voir to connect said moving means to said switch and for releasing said retaining means.

7. The combination with a fixed support, 5 of a reservoir adapted to contain material in melted form and to be moved back and forth with respect to said support to discharge the material, means controlled by an electric circuit for supplying melted material to said reservoir, a switch in said circuit, an operating member therefor mounted on said support, and a float controlled arm movable with said reservoir adapted to be shifted into and out of positions in which it 15 is engageable with the switch operating member whereby said switch may be actuated upon the movement of the reservoir.

8. The combination with a fixed support, 20 of a reservoir adapted to contain material in melted form and to be moved back and forth with respect to said support to discharge the material, means controlled by an electric circuit for supplying material to said reservoir, a switch in said circuit, and switch operating means comprising a member movable with said reservoir and a member on said fixed support adapted to be engaged and shifted by the first member on movement of said reservoir.

30 9. The combination with a reservoir adapted to contain material in melted form, of means controlled by an electric circuit for supplying melted material to said reservoir, a switch in said circuit, actuating members 35 associated with the switch, a part carried by a moving element of the machine and engageable with said actuating members, and means controlled by the level of the melted material in the reservoir for controlling the engagement of said part with said actuating members.

40 10. The combination with a fixed support, a reservoir adapted to contain material in melted form and to be moved back and forth with respect to said support, means 45 for supplying melted material to said reservoir, an electric circuit for controlling said melted material supplying means, a switch in said circuit, an arm pivoted on said reservoir, a float connected to one end of said arm, and a member mounted upon said support for operating said switch, said member being in position to be engaged by said arm in one position thereof and to be actuated upon movement of said reservoir.

55 11. The combination with a fixed support, a reservoir adapted to contain material in melted form and to be moved back and forth with respect to said support, means for supplying melted material to said reservoir, an electric circuit for controlling the melted material supplying means, a switch in said circuit, a switch operating member mounted 60 upon said support and movable in the direc-

tion of movement of said reservoir, an arm movable with said reservoir for actuating said member, means controlled by the level of melted material in said reservoir to vary the path of movement of said arm, whereby 70 said member will be actuated only when the melted material in said reservoir is at a predetermined level.

12. The combination with a reservoir adapted to contain material in melted form, 75 of means controlled by an electric circuit for supplying melted material to said reservoir, a switch in said circuit movable from open to closed position, a latch member for holding said switch in one of said positions, an actuating device for moving said switch into engagement with said latch member and a float controlled arm carried by the reservoir engageable with said actuating device when moved in one direction and with said latch member when moved in the opposite direction whereby said switch is opened and closed.

13. The combination with a reservoir 80 adapted to contain material in molten form, of a melting cup mounted above the reservoir and adapted to contain material in solid form, an electric resistance element associated with said cup, a switch controlling the functioning of said resistance element, 85 switch operating means, and means for connecting said switch operating means with said switch to operate the switch, said connecting means being controlled by the level of melted material in said reservoir. 90

14. The combination with a reservoir 95 adapted to contain material in molten form, of a melting cup mounted above the reservoir and adapted to contain material in solid form, an electric resistance element associated with said cup, a switch controlling the functioning of said resistance element, switch operating means provided with spaced switch shifting and switch releasing members, and a float controlled arm on said reservoir extending between the spaced members of said operating means and adapted to actuate one of said members when the level of the material in the reservoir reaches a predetermined high level and the other of 100 said members when the level in said reservoir drops to a predetermined level. 105

15. The combination with a reservoir 110 adapted to contain material in molten form, of a melting cup mounted above the reservoir and adapted to contain material in solid form, an electric resistance element associated with the cup, a switch controlling the functioning of said resistance element, a switch shifting means, a switch releasing means, float controlled means carried by said reservoir for connecting said shifting means with the switch to actuate the switch and for operating said releasing means. 115

16. The combination with a reservoir 120 130

adapted to contain material in molten form, means controlled by an electric circuit for supplying melted material to said reservoir, a switch in said circuit, separate means for 5 controlling the opening and closing of the switch, means responsive to the level of the molten material in said reservoir adapted to

actuate the switch opening and closing means, and means for locking said opening and closing means, against actuation by said 10 molten material level responsive means.

In testimony whereof, I hereunto affix my signature.

GEORGE E. LEE.
